UNITED STATES PATENT OFFICE.

ERNEST J. SWEETLAND, OF MONTCLAIR, NEW JERSEY.

METHOD OF AND APPARATUS FOR DEVELOPING FILMS.

Application filed November 15, 1919. Serial No. 338,268.

To all whom it may concern:

Be it known that I, ERNEST J. SWEETLAND, a citizen of the United States, residing in the town of Montclair, county of Essex, and State of New Jersey, United States of America, have invented certain new and useful Improvements in Methods of and Apparatus for Developing Films, of which the following is a specification.

This invention relates in general to apparatus for developing photographic film, and more particularly to apparatus of this character adapted to the developing of short strips of film, such as are usually supplied upon rolls for use with hand cameras.

The objects of the invention are to provide a film developing apparatus for mechanically moving the film through the developing solutions or causing the solution to flow over the film; to provide novel means for the mechanical manipulation of film developing devices, such as described in my United States Patent No. 1,285,462; dated Nov. 19, 1918 to secure means for developing large numbers of strips of film in rapid succession; to provide means for ensuring the thorough treatment of the film by the developing solutions; to ensure against under or over developing of the film by provision of mechanical means, whereby the film is subjected to treatment for predetermined periods of time; to secure means for producing the successive treatment of the film to the various solutions and to mechanically transfer same from one solution to another; to provide means for removing the film from the apparatus when completely developed; to secure the proper agitation of the solutions over the film; and to attain other objects and results as may be brought out by the following description.

Referring to the accompanying drawings, in which like numerals of reference indicate the same parts throughout the several views:

Figure 1 is a side elevation of a film developing apparatus showing one embodiment of my invention adapted for daylight developing with devices such as shown in my before-mentioned Patent No.

1,285,462;

Figure 2 is a front elevation thereof; Figure 3 is a view similar to Figure 1, showing a dark room developing apparatus, portions being shown in section;

Figure 4 is a front elevation of the apparatus shown by Figure 3;

Figure 5 is a vertical longitudinal sectional view through another embodiment of my invention;

Figure 6 is an end elevation thereof;

Figure 7 is a perspective view of the film enveloping device or bag used in connection with the apparatus shown by Figure 1;

Figure 8 is an enlarged plan view of the film attaching means shown by Figure 3;

Figure 9 is an enlarged side elevation of the film attaching or holding device used in connection with the apparatus shown by Figures 5 and 6; and

Figure 10 is a plan view of one end thereof.

Specifically describing the embodiment of the invention illustrated by Figures 1, 2 and 7, the numerals 1 designate a pair of spaced end standards or uprights which are formed in lower and upper sections 2 and 3, respectively, pivotally connected at 5 by a horizontal shaft 6 extending between the standards 1. Rigid with the upper sections 3 and supported thereby is a bed or table 7 upon which is mounted the film carrying belt 8 extending around roller pulleys 9 and 10 mounted on shafts 11 and 12, respectively, which are journaled in brackets 13 and 14, the said shafts extending transversely of the table 7 at the ends thereof. The shaft 12 is adjustable in the bracket 14 in a conventional manner to take up slack in the belt 8. Arranged between said belt roller pulleys 9 and 10, and under the upper reach of the belt are a series of transversely extending supporting rollers 8^a journaled in frames 8^b mounted on the table 7, said rollers supporting the intermediate portions of the belt between the pulleys.

The drive shaft 6 carries a worm wheel 15 which meshes with a worm 17 on the shaft of a conventional motor 18 so that the shaft 6 is rotated by the motor 18. One end of the drive shaft 6 is provided with a rigidly

connected crank arm 19 pivotally connected to one end of a link 20, the other end of which is pivotally connected, as at 21, to the end of the table 7, the said pivotal connection being adjustable in various openings 22 to vary the leverage of the link 20. Obviously, as the drive shaft 6 rotates, the table 7 is oscillated about the pivotal connections 5 of the standards 1. A belt pulley 23 is also fixed on the drive shaft 6 and is connected by a belt 24 to a pulley 25 mounted on a countershaft 26, journaled in brackets 27 depending from the table 7, the said countershaft also carrying a worm 28 meshing a worm wheel 29 on a stub shaft 30 journaled in a bracket 31 on the table 7. This stub shaft is provided with a sprocket 32 connected by a chain 33 to a sprocket 34 mounted on one end of the roller shaft 11. It will thus be seen that the film carrying belt 8 is also actuated over the rollers 9 and 10 by the motor 18.

The belt 8 is adapted to receive the films to be developed, the film being first placed in a flexible bag 35 (see Figure 7) as described in my United States Patent No. 1,285,462. One end of the film 36 is secured by a clip 37 in the bag 35 and the film unrolled or laid flat in the bag, after which the developing solution is poured into the bag and the free end thereof turned over and fastened externally by a clip 38, which holds the film extended. Assuming the belt 8 to be traveling in the direction indicated by the arrows, the bag 35 is then laid upon the upper reach of the belt 8, as shown by Figure 1, over the pulley 10. As the bag is being carried by the belt toward its other end, the table is being simultaneously oscillated by the crank arm 19 and link 20, so that the developing solution is constantly agitated over the film from one end of the bag to the other. The belt 8 is preferably sufficiently long so that by the time the bag 35 reaches the pulley 9, the film has been sufficiently treated by the solution. The bag is then removed from the belt, the developing solution poured out of the bag, and then the washing, fixing and final washing operations can be performed identically as described in connection with the developing solution. Obviously, the bags 35 can be successively applied to and removed from the belt 8 so as to constitute a continuous process, it being possible to develop large numbers of films in rapid succession. In case only one film is placed on the belt, the clip 38 can be provided with an extending finger 39 to engage an electric circuit closing device 40 at the finish end of the belt, and said circuit closer can be connected in a conventional way to a suitable alarm to warn the operator of the completion of the developing operation, so as to prevent over developing. With this apparatus, the tiresome manual manipula-

tion of the bags 35 is eliminated, the speed of developing large numbers of films increased, and the developing operation can be performed in daylight.

Another form of the invention adapted for dark room developing is shown by Figures 3, 4 and 8. In this form of the invention, the table 7 is provided with a pan or container 41 to receive the developing solution, and the shafts 11^a and 12^a are provided with sprockets 42, and arranged within the pan 41 over which sprockets are arranged spaced and parallel chains 43, which take the place of the belt 8. These chains 43 are provided with oppositely arranged spaced hooks 44 between which the films are suspended. In the use of this form of the invention, the film 45 is stretched between clips 46 and 47 (see Figure 8), one of said clips in the present instance, 46, being provided with an extension 48 having an opening 49 to receive one of the hooks 44 on chains 43, while the other clip 47 has connected thereto one end of a spring 47^a, the opposite end of which is provided with an eye 50 to fit over another of the hooks 44 on the opposite chain 43, as shown by Figure 3. In developing, the films are stretched between the chains 43 at one end thereof, the springs 47^a keeping them flat and straight, and as the chains are driven the films are drawn edgewise through the developing solution, which is agitated longitudinally over the films by oscillation of the table 7, as above described. The construction of this form of the invention is otherwise identical with that shown by Figures 1 and 2, and it is thought unnecessary to repeat the description thereof.

In both forms of the invention above described, it is necessary to either pour off the various solutions as they are used and supply the next successive solution, or provide a number of machines, one for each solution. This necessity is obviated by the construction shown by Figures 5, 6, 9 and 10. This construction comprises the standards 1, and oscillating table 7 exactly as above described and driving mechanism therefor, as shown by Figures 1 to 4, inclusive, further description of which is unnecessary. Supported by the table 7 is a container 51, said container being divided into compartments by transverse partitions 52, each compartment being adapted to receive a different solution, as for instance, the compartment 53 would contain the developing solution; compartment 54, the first wash water; compartment 55, the fixing solution, and compartment 56, the final washing water. The strips of film are drawn successively through these solutions by means of endless chains 57 driven from the motor 18. A pulley 58 is fixed to the drive shaft 6 and is connected by a belt 59 to a belt pulley 60 on a counter-

shaft 61 suspended from the table 6, said countershaft carrying a worm 61^a meshing with a worm wheel 62 on a sub-countershaft 63 also suspended from the table 6. This 5 sub-countershaft is provided with a sprocket 64 connected to a sprocket 65 on a stub-shaft 66 by means of a chain 67. A mutilated gear 68 is keyed to the stub-shaft 66 and meshes with a pinion 68^a on a short shaft 10 69, which shaft is provided with a gear 70 meshing with a pinion 71 on one end of one film chain shaft 72 arranged transversely of the container 51 adjacent one end thereof. A rectangular frame 73 is arranged 15 vertically upon the table 6 over the container 51, said frame supporting a plurality of idler sprockets 74^a on opposite sides thereof over which pass the pair of spaced and parallel film carrying chains 57, said chains 20 being driven from the sprocket 74 on the film chain shaft 72 before-mentioned.

The chains 57 are provided with spaced and oppositely disposed hooks 75 and normally travel in the direction of the arrow 25 on Figure 5, and the operator standing at the front of the machine beside a suitable stand or table 76 upon which the rolls 77 of films may be placed. The films are unrolled and the ends thereof fastened between a pair 30 of similarly formed clips 78, which are provided with eyes 79 to fit over the hooks 75 on the chains (see Figures 9 and 10). The films are then stretched between the chains 57 and the eyes 79 on the clips slipped on the 35 hooks 75, as shown by Figure 6. The chains then carry the films successively through the solutions in the container 51. The compartments of the container 51 are preferably sufficiently large that one passage of the films 40 through each completes the developing thereof, and the chains are driven with an intermittent motion by means of the mutilated gear 68 to allow longer periods of time in each solution, and also to allow the operator to easily attach the films to the chain 45 hooks, the stopping of the chains allowing sufficient time for this operation. The intermittent movement of the chain and the film, which is carried thereby through the 50 solutions, constitutes one of the important features of my invention. Obviously the stoppage of their travel not only facilitates the placing of the films in the machines but it also lends itself largely toward the efficiency of process of treatment of the film. 55 For instance, the time of the treatment of the film by the respective solutions may be controlled and regulated, so that maximum speed can be maintained in order that the machine can be utilized to greatest advantage. Furthermore, it is desirable to have the speed of motion such that the film after being properly developed in compartment 53 will pass entirely through the compartment 54, in which the film is washed of all

developing liquid before passing into the fixing solution in compartment 55. This is made possible by the intermittent motion mechanism heretofore described.

The arrangements may be such that the distance of travel of the film during the intermittent motion will cause the film to pass from the developing compartment 53 into the washing compartment 54 and there rest until the succeeding movement will carry it out of the wash water into the fixing solution compartment 55. In either case, it is important that the film be moved from the developing solution quickly so as to prevent oxidation and staining which would be incident to a slow movement of the film out of the developing solution.

After the films have been drawn through each of the solutions they are carried to the upper reaches of the chains and through a drying chamber 80 arranged at the top of the frame 73. At the rear end of this drying chamber is arranged a blower fan 81 which forces a current of air through the drying chamber over a heating coil 82. When the films reach the front end of the upper reaches of the chains 57 they are thoroughly developed and dried, and are ready for removal from the chains. This 95 can be accomplished manually or automatically. For automatically removing the films from the chains, a pair of vertical rods 83 are arranged on a suitable support 84 at the front of the machine, the upper ends of said rods being offset toward the chains and arranged in alignment with openings 85 in ears 86 projecting from the clips 78. As the ears 86 approach the rods 83, the openings in the ears slip over the ends of the rods, and downward movement of the chains then 100 draws the hooks 75 on the chains from the eyes 79 on the clips. The films and clips then slip downwardly by gravity on the rods 83 to the support 84, from where they 105 can be removed by the operator.

If desired, a brush 87 can be arranged in the compartment 53 to brush the solution over the films so as to remove any air bells or foreign matter that may have adhered to the film and to ensure proper treatment of the films thereby. The brush, in the present instance, is shown as pivotally mounted at its ends by links 88 on brackets 89 projecting inwardly from the frame, and is adapted to reciprocate transversely of the container 51 or longitudinally of the films with a brushing action, by any suitable means such as the connecting rod eccentrically connected to a disc 91 driven by a belt 92 from any suitable source of power.

It will be understood that the films are drawn successively through the solutions in the compartments by the chains 57 passing over the idler sprockets 74^a, and driven from the motor 18. Simultaneously with their

passage through the solutions, the films are thoroughly washed and treated therewith by agitation of the solutions by oscillation of the table 7 and container 51. Thus, this 5 form of my apparatus is adapted to carry an exposed film completely through a developing process to its drying, and it is obvious that a large number of films can be passed through the apparatus at the same time in 10 rapid succession. In all the forms of the invention, the fundamental idea is to eliminate the manual manipulation of films in the developing process by mechanical means which simulate the manual motions and 15 steps incident to a developing process. The solutions are mechanically moved over the films so as to insure thorough treatment, and the apparatus is constructed so as to continue the treatment through the proper periods of time. All the operations that are 20 necessary for the operator to perform are the insertion and the removal of the films from the apparatus.

Obviously many detail modifications and 25 changes can be made in the construction of my apparatus without departing from the spirit and scope of the invention, and I do not desire to be understood as limiting myself except as required by the following 30 claims when construed in the light of the prior art.

Having thus described my invention what I claim as new herein and desire to secure by Letters Patent is:

35 1. In a film developing apparatus, the combination of a receptacle to receive film treating solution, means for holding a strip of film unrolled in position to be immersed in said solution, means for maintaining said 40 solution in motion while the film is immersed therein, and means for moving said film transversely to its length simultaneously with said motion of the solution.

45 2. In film developing apparatus, the combination of a receptacle to receive a film treating solution, means for immersing a film in said solution, and means for bodily moving said film edgewise, said moving means regulating the period of immersion of 50 the film.

55 3. In film developing apparatus, the combination of a receptacle to receive a film treating solution, means for moving said receptacle, and means for immersing a film edgewise in said solution in the receptacle while said receptacle is in motion.

60 4. In film developing apparatus, the combination of a receptacle to receive film treating solution, means for immersing a film in said solution and means for moving said film a predetermined distance edgewise while so immersed, the movement of said film over said distance consuming a period of time necessary for treatment of the film in said 65 solution.

5. In film developing apparatus, the combination of a receptacle to receive film treating solution, means for maintaining said receptacle in motion to agitate the solution, and means for moving a film edgewise 70 through said solution while the same is agitated.

6. In film developing apparatus, the combination of a receptacle to receive film treating solution, a pair of spaced conveyor 75 members movable through said solution, and means for supporting a strip of film between said members for moving the film through said solution.

7. In film developing apparatus, the combination of a receptacle to receive film treating solution, a pair of spaced conveyor members movable into and out of said solution, means for regulating the period of their movement in said solution, and means 85 for supporting a strip of film between said members.

8. In film developing apparatus, the combination of a receptacle to receive film treating solution, a pair of spaced endless members, a portion of each of which passes through said solution, and means for supporting a strip of film between said members.

9. In film developing apparatus, the combination of a receptacle to receive film treating solution, means for maintaining said receptacle in motion to agitate the solution, a pair of spaced members movable through said liquid and rigidly supported with respect to said receptacle, and means for connecting a strip of film between said members.

10. In film developing apparatus, the combination, of a plurality of receptacles, 105 each to receive a different film treating liquid, and means for moving strips of film in continuous succession edgewise through the solutions in each of said receptacles.

11. In film developing apparatus, the combination of a receptacle to receive film treating solution, a film carrying mechanism to move films edgewise through said solution and means for actuating said film carrying mechanism with an intermittent motion.

115 12. In film developing apparatus, the combination of a plurality of receptacles, each adapted to contain a different film treating solution, and means for moving strips of film successively edgewise through said receptacles, the length of travel of the film through each receptacle consuming a period of time sufficient for proper treatment of the film by the solution in that receptacle.

13. In film developing apparatus, the combination of a receptacle to receive film treating solution and strips of film in parallel relation, of means for moving the strips of film through the solution in a direc- 130

tion transverse to their length, brush means adapted to engage the surface of the films and means for imparting oscillating movement to the brush means in a direction parallel to the film.

14. The method of film development which consists in arranging a plurality of strips of film in parallel relation and passing them through film treating solutions

always in a direction transverse to their length.

15. The method of film development which consists in arranging a plurality of strips of film in parallel relation and passing them through film treating solution with a step-by-step or intermittent motion transversely to their length.

ERNEST J. SWEETLAND.
